Primary Examiner—Marianne Pandozzi

(74) *Attorney, Agent, or Firm*—McGuire Woods LLP

(57) **CLAIM**

We claim the ornamental design for a mug, as shown and described.

DESCRIPTION

FIG. 1 is a front top side perspective view of the mug;

FIG. 2 is a top view of the design embodiment shown in FIG. 1;

FIG. 3 is a bottom view of the design embodiment shown in FIG. 1; and

FIG. 4 is a front view of the design embodiment shown in FIG. 1.

FIG. 5 is a front, top, side perspective view of a mug showing a second embodiment of my new design;

FIG. 6 is a top view of the design embodiment shown in FIG. 5;

FIG. 7 is a bottom view of the design embodiment shown in FIG. 5; and,

FIG. 8 is a front view of the design embodiment shown in FIG. 5.

The broken lines in the drawings are included for the purpose of illustration and form no part of the claimed design. The break lines in FIGS. 5 and 8 are to show indeterminate length.

1 Claim, 6 Drawing Sheets
